UNITED STATES PATENT OFFICE.

GEORGE D. FOGARTY, OF BROOKLYN, NEW YORK.

DESIGN FOR A SIGNAL.

52,607.

Specification for Design.

Patented Oct. 29, 1918.

Application filed June 21, 1917. Serial No. 176,242. Term of patent 14 years.

To all whom it may concern:

Be it known that I, GEORGE D. FOGARTY, a citizen of the United States, residing at Brooklyn, in the county of Kings and State of New York, have invented a new, original, and ornamental Design for a Signal, of which the following is a specification, reference being had to the accompanying drawing, forming part thereof.

The figure is a front elevation of a signal, showing my new design.

I claim:

The ornamental design for a signal, as shown.

GEORGE D. FOGARTY,

Witnesses:

JOHN ROBERTSON,
JOHN F. KERNAGHAN.
